UNITED STATES PATENT OFFICE.

THOMAS H. ROBBINS, OF LADYSMITH, WISCONSIN, AND EUGENE P. ROBBINS, OF MINNEAPOLIS, MINNESOTA.

PROTECTING DEVICE FOR BANK-WINDOWS.

1,382,803.

Specification of Letters Patent. Patented June 28, 1921.

Application filed August 25, 1919. Serial No. 319,633.

To all whom it may concern:

Be it known that we, THOMAS H. ROBBINS and EUGENE P. ROBBINS, citizens of the United States, residing at Ladysmith, in the 5 county of Rusk, State of Wisconsin, and Minneapolis, in the county of Hennepin, State of Minnesota, respectively, have invented certain new and useful Improvements in Protecting Devices for Bank-Windows; 10 and we do hereby declare the following to be a full, clear, and exact description of the invention, such as will enable others skilled in the art to which it appertains to make and use the same.

15 Our invention has for its object to provide an improved protecting device for bank windows, said latter term being used in a broad sense to include any window or like opening through which money or valuables 20 are to be passed. Particularly, the invention is designed to protect bank tellers' windows in banks.

The teller's window in a bank is usually covered with a grating and heavy plate glass 25 that is customarily extended at both sides of the window. It has frequently happened, however, that a robber suddenly appearing at the window will thrust his revolver through the grating, aim directly at the 30 teller, with a demand that the money be delivered to him through the window and usually this request is complied with because of the very great risk incident to refusal.

Our invention provides a device which, 35 while normally out of the way and nearly or quite invisible, may, by an unobserved foot operation of the teller, be tripped, and when thus released, will instantly fly to a position to close the window and afford a 40 bullet-proof protection between the robber and the teller. This window closing and protecting device will preferably be made of, probably, hardened sheet steel hinged at its upper edge and under spring tension to 45 close but yieldingly held by a latch adapted to be tripped, as above generally indicated. A lock is provided for automatically locking the protector plate in its window closing position.

50 The invention is illustrated in the accompanying drawings wherein like characters indicate like parts throughout the several views:—

Figure 1 is a view chiefly in elevation but 55 with some parts sectioned, showing the win-

dow protector applied to a teller's window, said parts being viewed from the teller's side of the window;

Fig. 2 is a vertical section taken on the line 2—2 of Fig. 1;

Fig. 3 is a horizontal section taken on the line 3—3 of Fig. 1, some parts being broken away;

Fig. 4 is a horizontal section taken approximately on the line 4—4 of Fig. 1; and

Fig. 5 is a plan view showing in detail the trip bar of the protecting mechanism, some parts being broken away.

The teller's cage is of the usual or any suitable construction, and of the parts thereof, it is only desirable to particularly note the window counter 6, the front panel or wall 7, the glass front panes 8, side walls 9, and the window frame 10, which latter affords the opening for the teller's window. 75 The window grating is indicated by the numeral 11.

The window grating 11 has a transverse intermediate bar 11^a, and to this bar the metal protecting plate 12 is hinged at 13. 80 The distance between the hinge 13 and the counter 6 is such that the protecting plate 12, when swung downward, will but slightly clear the said counter; and to lock said protecting plate in its downturned dotted line 85 position, Fig. 2, to thereby close the window opening, one or more latches are applied to the counter. These locks, as shown, are two in number and are afforded by bent leaf springs 14 attached at one end of the counter 90 with their free ends in position to be engaged and depressed by the protecting plate when the latter is swung downward, and when the protecting plate reaches its extreme closed position, these spring locks or 95 latches 14 will securely hold the same in such position.

Normally, the protecting plate 12 will be raised and held in a raised position. This raised position may be anywhere between a 100 horizontal position and an upturned vertical position, and preferably it is normally secured in approximately the latter noted position, by means of a hook-like latch arm 15 secured to a small rock shaft 16 journaled 105 in suitable bearings afforded by the inturned ends of a bar 17 secured to the upper portion of the framework 10. At one end, a rock shaft 16 is provided with an arm 18 that projects in a direction opposite to the 110

latch arm 15. This arm 18 is connected to the upper end of a cord or tripping connection 19 that extends downward through the counter, and at its lower end is attached to one end of a tripping bar 20. This tripping bar stands normally slightly above the floor, and when stepped upon, will operate through the cable 19 and rock shaft 16 to raise latch arm 15 and release the protecting plate 12.

The protecting plate 12 is under normal spring pressure to quickly fly to its down-turned closed position under the action of a propelling spring. As shown, there are two of these propelling springs 21 in the form of leaf springs secured at their lower ends to the side bars of the window frame 10. These springs 21 are put under considerable strain when the protecting plate 12 is in its upturned position shown in Fig. 2.

A pair of flanged guide columns 22 are extended from the counter 6 down to the floor and the prongs of these columns are provided with L-shaped notches 23 and 24. When the tripping bar 20 is placed in the lower notches 23, it will drop to the bottom of one of the notches at one end, and its other end, to wit, that end secured to the cable 12, will be free for vertical movements. To hold the latter noted end of the tripping bar normally raised slightly above the bottom of its cooperating notch 23, said tripping bar is shown as provided with a leaf spring 25 that engages the floor, as shown in Fig. 1. When the tripping bar 20 is stepped on, this spring 25 will be bent and the protecting plate will be released, as already described.

Sometimes, as when scrubbing or sweeping the floor, it is desirable to get the tripping bar out of the way, and it may then be raised and inserted into the upper notches 24 of the columns 22.

The operation is thought to be obvious from the foregoing statements, but the following further comments may be made. Normally, the protecting plate 12 will be raised so that the cashier's window may be used in the usual way. The teller will usually be standing near the window and close to the counter.

If a robber should point a revolver at the teller through the window, the teller, by movements of the foot, not observed by the robber, will press the trip bar 20, thereupon, as quick as a shot, the said protecting plate will be released and thrown downward to a closed position and there locked. This will completely cut off all direct line of vision between the robber and teller and would give the teller plenty of chance to drop behind the counter and escape or do

any other thing desirable under the circumstances.

The robber will hardly shoot through the 65 glass window plates, but if further protection is required, these glass plates will be dispensed with and other provision made for protection at such points. The hinged edge of the protecting plate 12 is so high up 70 that a robber could not see over the same, but, nevertheless, the teller's window down to the hinge might have any desired solid closure for further protection.

The device described is, of course, capable of modification within the broad scope of my invention and could be modified as to manner of application, dimensions, and the like, to better adapt it for application to various different places and different types 80 of windows. The device is adapted generally for application to all small window openings that require protection against robbers.

What we claim is:

1. The combination with the framework of a bank window having a window opening therein and a stationary counter at the bottom of said opening, of a normally elevated protecting plate extending upwardly 90 from the top of the window opening and hinged to the window frame adjacent the top of the said opening, means above said window opening for holding said plate in its normal position, said plate being adapted to swing downwardly to close the window opening, means tending to swing said plate to its closed position when the same is released, a tripping means for releasing said plate to permit it to swing to closed 100 position, and locking means on said counter to hold the plate in closed position.

2. The combination with a window and a counter at the bottom thereof, of a protecting plate hinged in respect to said window 105 at one edge and under yielding strain to move to a window closing position, a latch for securing said protecting plate in a window opening position, guide columns below said counter, a tripping bar removably 110 mounted on said columns, said columns having upper and lower seats with either of which said tripping bar may be engaged at will, and a cable connecting said tripping bar to said latch by releasing said protecting plate.

In testimony whereof we affix our signatures in presence of two witnesses.

THOMAS H. ROBBINS.
EUGENE P. ROBBINS.
